UNITED STATES PATENT OFFICE.

EDWARD A. GUTERMANN, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A LEG FOR A COFFEE-URN, CHAFING-DISH, OR SIMILAR ARTICLE.

40,642.

Specification for Design.

Patented Apr. 19, 1910.

Application filed February 15, 1910. Serial No. 544,137. Term of patent 7 years.

To all whom it may concern:

Be it known that I, EDWARD A. GUTERMANN, a citizen of the United States, residing at Meriden, county of New Haven, State of Connecticut, have invented a new, original, and ornamental Design for a Leg for a Coffee-Urn, Chafing-Dish, or Similar Article, as herein set forth.

In the accompanying drawings: Figure 1 is a front elevation of a leg showing my new design; Fig. 2 is a side elevation thereof.

I claim—

The ornamental design for a leg for a coffee urn, chafing dish or similar article, as shown.

EDWARD A. GUTERMANN.
